UNIVERSALLY ADJUSTABLE LAMP

James H. Cannon, Los Angeles, Calif.

Application June 12, 1933, Serial No. 675,440

1 Claim. (Cl. 240—53)

My invention relates to a lamp which is universally adjustable so that the light beam thereof may be cast in any direction, and having a shade or reflector means whereby a very complete control of the light beam may be obtained. The preferred form of my invention is embodied in a portable lamp structure adapted to be readily secured to objects, such as the head frame of a bed, the back of a chair, or the edge of a shelf. In addition to the features thereof which will be hereinafter fully described, the adjustable lamp is of compact form and of such design as to have a pleasing appearance.

It is an object of the invention to provide a universally adjustable lamp in which a relatively complete control of the light beam may be attained, with regard to both the direction of the light beam and the size thereof. It is a feature of the lamp that means are embodied therein for definitely cutting off the light beam in any desired plane so that a strong light will be projected above the plane of control, and the space below such plane will be relatively dark or illuminated entirely by reflected light.

It is a further object of the invention to provide an adjustable lamp of the above character having an improved form of shield or reflector made from cooperating overlapping cup-shaped parts hingedly related so as to produce the control of the light beam set forth in the preceding paragraph.

Further objects and advantages of the invention will be made evident throughout the following part of the specification.

Referring to the drawing, which is for illustrative purposes only,

Fig. 1 is a side view of the preferred embodiment of my invention, partly sectioned in a vertical plane.

Fig. 2 is a face view corresponding in part to Fig. 1 but showing the base member of the lamp structure secured to a diagonal member.

Fig. 3 is a side view similar to Fig. 1 drawn to slightly reduced scale and showing the adjustable shield member in relatively closed position.

Fig. 4 is a side view showing the manner in which the lamp may be secured against a wall and showing the light controlling means thereof in position to direct the light beam to one side of a vertical plane and above a horizontal plane.

Fig. 5 is a view of the lamp showing the parts thereof adjusted for use on a table.

As shown in the drawing, my invention provides a lamp globe 10 of commercial type carried on a universally adjustable supporting means, broad-

ly designated by the numeral 11, so as to permit a rotation of the lamp 10 relative to a vertical axis and a horizontal axis. The adjustable supporting means 11 comprises a base member 12 adapted to be secured to a stationary object such as a pipe 13 constituting a frame member of a bedstead, and a supporting bar 14 secured to the base member so as to rotate on a defined axis A—A, which axis is preferably perpendicular to the plane of the base member 12. The supporting bar 14 is rotatably secured to the base member 12 by a simple means which operates frictionally to resist rotation of the bar 14 whereby to yieldably hold such bar 14 in any position to which it has been adjusted. This securing means 15 for the bar 14 comprises a tubular stem 15 projecting rearwardly through an opening 16 in the front wall 17 of the base member 12 from a shoulder 18 formed near the rearward end of the bar 14. In the inner face of the wall 17 a shallow counterbore 19 may be formed, and in this counterbore 19 a cupped spring washer 20 is placed around the inwardly projecting portion of the tubular stem 15, and the annular edge or lip 21 of the tubular stem 15 is flanged outwardly over the metal of the spring washer 20 surrounding the opening of the spring washer through which the tubular stem 15 extends. In this manner the spring washer 20 is placed under stress so as to continuously exert a resilient force for holding the shoulder 18 of the bar 14 against the outer face of the wall 17, the frictional engagement of these parts serving to yieldably hold the bar 14 in its adjusted position relative to the base member 12. For detachably receiving the lamp globe 10, a commercial lamp socket 22 is employed, such lamp socket having switch means therein adapted, in accordance with standard practice, to be actuated by means of a laterally slidable actuating pin 23. The shell of this lamp socket differs from standard lamp sockets in the provision thereon of a rear end cap 24 having a cord outlet 25 extending laterally therefrom instead of being aligned with the axis of the lamp socket 22, so that the lamp cord 26 will be projected laterally from the socket 22 instead of rearwardly therefrom. By means of a pair of projecting tongues 27, which are preferably formed on the ends of a substantially circumferential band 28 secured around the body of the lamp socket 22, such lamp socket is secured to the outer end of the supporting bar 14. The bar 14 is flattened as indicated at 30 so that a pivot member, which may be in the form of a screw 31, may be employed to clamp the tongues or lugs 27 against flat faces so as to produce a

frictional engagement sufficient to resist free movement of the lamp socket 22 relative to the end of the bar 14. The screw 31 extends perpendicularly to the axis A—A. The socket 22 may be 5 rotated on the axis A—A through a plane parallel to the face of the wall 17, and on the pin 31 the lamp socket 22 may be rotated on an axis which crosses the axis A—A, thereby permitting the lamp socket 22 and the lamp globe 10 carried 10 thereby to be rotated into the various positions relative to the base 12 shown in Figs. 2 to 5.

Mounted on the socket 22 is a light controlling or shield device 33 comprising a primary member 34 and a secondary member 35. The primary member 34 is of cup shape and is preferably semi-spherical and of such diameter that it will fit essentially halfway around the lamp globe 10. This primary member 34 comprises a shield for half the space around the filament of the lamp globe 10 and is rotatable on a defined axis relative to the lamp globe, such axis preferably being the axis B—B of the socket 22 which passes centrally through the filament of the lamp globe 10. My invention provides a simple means for so mounting the primary shield member 34, such means consisting of an annular wall 36 disposed around the axis B—B and having an inwardly turned edge 37 at the upper or outer end thereof, as shown in Fig. 1, frictionally engaged in a groove 38 formed 20 in a ring 39 carried by the socket 22. In its preferred form the ring 39 is internally threaded and is screwed upon external threads 40 formed at the lower end of the lamp socket 22. The primary shield member 34 may rotate entirely around 25 the axis B—B and likewise around the lamp globe 10 so that the opening 41 thereof may be faced in any desired direction. The primary shield member 34 therefore provides a light control means for cutting off the light from the globe 10 behind 30 a plane C—C which is at all times parallel to the axis B—B and rotates around the axis B—B as the primary shield member 34 is rotated in the described manner. The secondary shield member 35 is also of cup-shaped form and is rotatably 35 mounted on the shield member 34 so that it may be swung from a non-closing to a closing position relative to the opening 41 of the primary shield member 34. This secondary shield member 35 is preferably also of hollow semi-spherical form 40 and is of slightly larger diameter than the primary shield member 34 so that it may be placed thereover in a manner to entirely cover the external face of the member 34 and in such position, 45 as shown in Fig. 2, that the opening or lip 42 thereof will coincide with the plane C—C defined by the lip or opening 41 of the primary shield member 34. For pivotally carrying the secondary shield member 35, pivot pins or rivets 43 are located on an axis D—D which is perpendicular to 50 the axis of rotation B—B and is diametral with respect to the semi-spherical shield members 34 and 35. These pivot pins 43 pass through edge portions of the members 34 and 35 and through 55 spacer washers 44 which are disposed between such edge portions, and heads are formed on the ends of the pivot members 43 for holding them in place and for causing the frictional engagement of the shield members 34 and 35 with the 60 spacer washers 44, the purpose of such frictional engagement being to resist free movement of the secondary shield member 35 relative to the primary shield member 34.

As shown in Fig. 1, the leftward portion of the 65 secondary shield member 35 has a semi-circular

notch 45 cut therein, of a diameter slightly larger than the cylindrical supporting shell 36 so that as the leftward portion of the secondary shield member 35 is rotated upwardly so as to bring the lips or openings 41 and 42 into alignment, the 5 semi-circular notch 45 will lie over essentially half of the lower edge of the cylindrical part 36.

The construction described in the foregoing permits the secondary shield member 35 to be rotated from a position such as shown in Fig. 2, 10 in which the opening 41 of the primary shield member 34 is entirely disclosed, through intermediate positions such as shown in Figs. 1, 4, and 5, to a position such as shown in Fig. 3 in which the opening 41 of the primary member 34 is almost closed. Therefore, the primary and secondary shield members 34 and 35 cooperate to provide a control of the direction and quantity 15 of light rays issued from the adjustable lamp structure.

It is a feature of the invention to provide the base member 12 with a plurality of securing means one of which is in the form of a clamp 47 having a curved portion 49 bent from a flat metal wall so as to cooperate with curved notches 50 20 formed in the side walls 51 which extend rearwardly from the front wall 17 of the base 12. The clamp 47 includes an essentially flat wall 53 25 extending downwardly from the inner or lower edge of the curved wall 49, this flat wall 53 having walls or flanges 54 bent outwardly into planes perpendicular to the flat wall 53, there being openings in the lower ends of the edge walls 54 for receiving a pin 55 which extends across the inner space 56 of the base member 12 from one side wall 30 51 to the other thereof. A coil spring 57 is placed 35 around the pin 55, and the ends 58 and 60 of this spring 57 are disposed so as to press respectively against the wall 53 of the clamp 47 and the front wall 17 of the base member 12 so as to resiliently 40 urge the clamp 47 toward the inner face of the wall 12, whereby to normally hold the clamp 47 within the space 56 of the base member 12, as 45 shown in Figs. 3, 4, and 5. The curved notches 50 in the side walls 51 of the base member 12, in addition to cooperating with the clamp 47 in the engagement of a supporting member such as the pipe 13, also provide side openings through which a thumb and finger may be moved readily into engagement with the curved wall 49 of the clamp 50 47 for the purpose of pulling the clamp 47 into an extended position in preparation to engaging 55 a supporting member.

In Fig. 1 the adjustable lamp structure is shown 55 in the position which it may assume on a bedstead above the head of a person lying in the bed. When the lamp is so placed, the head of the reclining person is below the lamp globe 10. Rotation of the primary shield member 34 into the position in which it is shown in Fig. 1 will result 60 in controlling the issue of light rays in a forward direction, and the adjustment of the secondary shield member into the intermediate position shown in Fig. 1 will control the downward passage 65 of light rays. The lip or opening 42 of the secondary shield member will cut off the light below a plane indicated by the dotted line E, thereby preventing the light from striking the eyes of a person reclining in the bed but permitting a complete illumination of an object held in the hands 70 of the reclining person. The lamp, adjusted as shown in Fig. 1, may serve two persons lying side by side in the bed. Should one of these persons desire no direct light in his direction, as in the case where one person desires to go to sleep while 75

the other desires to read, the primary shield member 34 may be rotated on the axis B—B so that the opening 41 of the primary shield member 34 will be sidewardly directed, thereby cutting off all direct light in the direction of the person desiring to sleep but maintaining a control of the light in the direction of the person desiring to read in such a manner that the light rays will strike the face of the book held by, but not in the face or eyes of, the person desiring to read. It will be recognized that my light structure provides a primary shield member 34 which is so mounted by the base 12, the bar 14, and the pivot screw 31 that the opening or lip 41 thereof may be moved into any desired plane, and that likewise the secondary shield member may be moved into any desired plane due to the ability of the respective parts of the lamp structure to rotate in a plurality of planes. Accordingly, in the use of the lamp structure the primary shield member 34 may be disposed with its lip 41 in any desired upright or essentially vertical plane, and the secondary shield member 35 may be rotated to cut off the light above or below an essentially horizontal plane. In Fig. 4 the primary shield member 34 is disposed sidewardly, and the secondary shield member 35 is so placed as to cut off a downward passage of light. As shown in Fig. 5, the entire lamp structure may be inverted, and the secondary shield member 35 may be disposed so as to cut off the light above a horizontal or essentially horizontal plane. The lamp structure provides a facile and quick adjustment into any desired light controlling position. It is especially useful for the purpose hereinabove set forth, and when used on a table in the position essentially shown in Fig. 5, it is of especial value to draftsmen as it will control a beam of light across a drawing but completely guard the eyes of the worker from such light. Where a small amount of light is desired, as, for instance, a night light, the secondary shield member 35 may be rotated into the substantially closed position in which it is shown in Fig. 3. At

this time small beams of light will issue from the triangular openings 65 existing between the upper parts of the lips 41 and 42. In the case of an emergency call, an awakened sleeper desiring more light is not required to search around for a light button but reaches directly to the source of light, namely, the small openings 65, and quickly moves the secondary shield 35 into a relatively open position.

As hereinbefore described, the adjustable lamp 10 may be mounted on rod or bar members, as shown in Figs. 1 and 2, or may be used as a table lamp, as shown in Fig. 5. In addition to this, it may be readily hung upon a wall, and for this purpose a slotted plate 66 is provided within the end of the 15 space 56 opposite to the clamp 47, the slot 67 of this plate 66 being adapted to engage the projecting portion of a screw or nail 68 which is placed in the face of a wall member 70, as shown in Fig. 4.

I claim as my invention:

An adjustable lamp of the character described, including: a base; a lamp globe; a socket for said lamp globe; a bar connecting between said base and said socket for universally supporting said socket on said base, said base having a recess in the bottom thereof; a clamping plate swingably secured to the base so as to swing in and out of said recess; spring means on said base engaging said clamping plate for urging said clamping plate toward said recess; a cup-shaped shield rotatably secured to said socket in a position partly surrounding said lamp globe and so as to rotate on the axis through said lamp globe and said socket; and a second cup-shaped shield rotatably mounted in a position partly surrounding said lamp globe so as to swing relative to said first named shield on an axis disposed in a plane essentially perpendicular to said first named axis, whereby to relatively close and disclose the opening of said first named shield.

JAMES H. CANNON.
